UNITED STATES PATENT OFFICE.

ALFRED G. BROWN, OF WINONA, MINNESOTA, ASSIGNOR TO UNION FIBRE COMPANY, OF WINONA, MINNESOTA, A CORPORATION OF MINNESOTA.

APPARATUS FOR MANUFACTURING HEAT-INSULATING LININGS OR COVERINGS.

974,858.

Specification of Letters Patent.

Patented Nov. 8, 1910.

Application filed August 9, 1909. Serial No. 512,030.

To all whom it may concern:

Be it known that I, ALFRED G. BROWN, a citizen of the United States, residing at Winona, in the county of Winona and State 5 of Minnesota, have invented certain new and useful Improvements in Apparatus for Manufacturing Heat-Insulating Linings or Coverings; and I do hereby declare the following to be a full, clear, and exact description of the same, reference being had to the accompanying drawings, forming a part of this specification, and to the figures and letters of reference marked thereon.

This invention relates to apparatus for 15 manufacturing heat insulating linings or coverings, and particularly linings such as are made use of in refrigerator or cold storage cars and buildings, the objects of the invention being to provide a means 20 whereby not only may an insulating material of higher efficiency be produced, but the product will be made uniform in quality, susceptible of being handled without injury, and not liable to deteriorate by decay nor 25 disintegrate from shocks and vibration.

A further object of the invention is to reduce the cost of production, thereby giving to the public a commercial product at a cost 30 which will permit a general use of the material wherever heat insulation is necessary or desired.

In the accompanying drawings—Figure 1 is a longitudinal sectional view through a 35 machine for carrying the present invention into practice, the parts being shown in outline and more or less diagrammatically, inasmuch as the means whereby the parts are supported is readily understood. Fig. 2 is a diagrammatic view illustrative of the 40 shape of the teeth on the disintegrating and transferring rollers and cylinders. Fig. 3 is a similar view illustrative of the shape of the teeth on one of the rollers to be hereinafter referred to.

Like letters of reference in the several 45 figures indicate the same parts.

The insulating material is fibrous and is composed of flax fiber preferably without additions or adulteration by additions of 50 substances not found in the flax plant itself. In the preparation of the fiber preliminary to the treatment in accordance with the present invention, the flax straw or plant is treated in a manner to eliminate more or 55 less completely the vegetable gum which

causes the adhesion between the fibers and between the fibers and woody portions or sheaves. The treatment is preferably a known chemical treatment in a digester in the presence of heat, followed by washing 60 and drying.

The degummed product, by which is included a product from which a substantial proportion of the gum has been removed, or from which a sufficient quantity of the vegetable gum has been removed to permit of the separation of the fibers, is then subjected to the action of mechanical appliances which will separate or disintegrate, distribute, and thoroughly commingle the fibers without 70 combing the same, the process in this respect differing from the usual hackling process in which the fibers are straightened out or combed and the long and short fibers separated from each other. This disintegration of the fiber reduces it to a flocculent condition, in which condition the fibers are susceptible of felting to a sufficient degree to form a loose thick blanket in which a large 75 part of the cellular and woody material will 80 be entangled and serve to give body and insulating qualities to the material. The flocculent fiber is formed into the felt or blanket in a dry state by air suction acting through coöperating foraminous cylinders and is then 85 led off through pressure rollers ready for the application of protecting coverings of paper.

In the machine illustrated in the drawings, the degummed straw is distributed by hand or suitable mechanical means on a 90 feed belt A by which it is carried to feed rollers B. In front of the feed rollers and in position to take the fiber therefrom is a cylinder C having forwardly projecting teeth (such as c shown in Fig. 2) and rotating 95 at a high surface speed as compared with that of the feeding rolls. To prevent the fiber leaving the cylinder immediately above the feed rolls and to hold the same until taken by the cylinder, a somewhat 100 smaller roller D is located immediately above the feed rolls and the surface of this roller D is provided with radial V-shaped teeth d as shown in Fig. 3. Roll D has a 105 surface speed less than the feed rolls and its direction of rotation is opposite to the direction of rotation of the cylinder.

At the top of the preliminary cylinder C a pair of rolls E, E' are located in position for their forwardly directed teeth (Fig. 2) 110

to act on the fiber carried by the cylinder, said rollers E—E' being rotated in a direction tending to move the fiber reversely on the cylinder but as they rotate with a much slower surface speed, the fiber will not be transferred to them but will be disintegrated and torn apart by them.

Immediately after being acted on by the rollers E—E' the now partly disintegrated fiber is transferred from the cylinder C to a main and larger cylinder F also provided with forwardly projecting teeth (Fig. 2). The transfer is effected by a transfer roller G, the surface of which is in proximity to both the cylinders C and F, and moves at a higher speed than the cylinder C and at a lower speed than the cylinder F. The transfer roller is also provided with forwardly directed teeth (Fig. 2) and is rotated in a direction whereby its surface will move in the same direction as the surfaces of the cylinders.

The cylinder F rotates at a very high rate of speed thus, as compared with the cylinder C which may have a diameter of nineteen inches and a speed of rotation of one hundred revolutions per minute, it would be thirty inches in diameter and have a speed of rotation approximately two hundred and eighty per minute. Between the point where the partially disintegrated fiber is delivered to the cylinder F, and the point where the fiber is removed from said cylinder, as will be presently described, it is subjected to the action of a series of rolls all of which have forwardly directed teeth (Fig. 2) and some of which rotate in one direction and some in the other. As illustrated, the rolls H—H', H²—H³, H⁴—H⁵, all rotate in the same direction and their surfaces in proximity to the cylinder move reversely to the movement of said cylinder surface but at a much slower speed. Each of said rollers is conveniently made six inches in diameter and rotate at approximately thirty revolutions per minute. Between the rollers H—H', H²—H³, H⁴—H⁵ intermediate rollers I, I', I² are arranged and rotate in the opposite direction with a higher surface speed than the speed of the rollers H, etc., but a much lower surface speed than the surface speed of the cylinder F. These intermediate rollers I, etc., are preferably of somewhat smaller diameter than the rollers H, and operate to clean the said rollers H, etc., of any adherent fiber and return the same to the cylinder F. In addition, they serve to still further disintegrate the fiber, distribute the same and reduce it to a flocculent condition.

The rollers H and I are distributed over the upper circumference of the cylinder and the fiber is removed from the cylinder by a high speed wiper or brush K having radial wiper arms k working in proximity to the

surface of the cylinder immediately below the series of rollers hereinbefore described. To prevent the entry of fiber into the arms of the brush or wiper the spaces between said arms are bridged by diaphragms k' which form flat faces between the projecting ends of the wipers 6 and force the fiber to follow around the periphery of the wiper. This brush or wiper K is mounted to work in a casing L with the inner face of which the ends of the wipers move in close proximity and said casing at the side opposite the cylinder F opens into a tangentially arranged and flaring duct M through which duct the fiber will be discharged. To provide a sufficient means for carrying the fiber through the duct and depositing the same the said duct is put into communication with a suction box and a grated air inlet opening N is provided in the bottom of the casing immediately below the brush. The gratings or slats n in this opening are arranged in an inclined position so as to prevent the exit of fiber and at the same time permit of the free entry of air which, under atmospheric pressure, will carry the fiber along and project the same through the discharge duct. The discharge duct terminates in top and bottom casing M'—M², with which the suction or exhaust chamber O communicates through openings o and in these casings two foraminous cylinders E—E' are journaled. The exhaust takes place through the cylinders themselves, the air being drawn from the duct through the foraminous cylinder walls and thence into the exhaust chamber. The cylinders run in proximity to each other and the entrance of air around them is prevented by barriers or end walls m in the casings.

Fiber discharged from the cylinder F by the brush and carried thence by the air pressure through the duct will be deposited on the foraminous surfaces of the cylinders and as said cylinders are rotated in opposite directions toward each other, the fiber deposited on the two cylinders will be brought together and pressed into a single sheet or blanket at the point where it passes between the cylinders. To prevent any continued adhesion of the fiber to the cylinders internal barriers or segmental air shields Q extend from the proximate points of the cylinders on their inner sides forwardly and outwardly to a point opposite the ends of the casing. Throughout these portions of the cylinders protected by the internal shields there is no inward movement of air and the fiber is free to leave the cylinders. As the fiber passes from the cylinders in the form of a blanket or sheet it is led through between guide rollers R—R', and S, S' said rollers, however, being preferably simply loose guide rollers rotated only by contact with the moving blanket or sheet of

fiber. To support the blanket or sheet of fiber after leaving the cylinders and between the pairs of rollers a guide plate T is provided over which the blanket or sheet is 5 pushed by the rotation of the foraminous cylinders themselves.

Obviously, the sheet or blanket, after passing through the guide rollers, may be folded or rolled in any convenient manner but it is 10 preferably rolled by having its end passed around a bar U guided in a vertical plane by a weighted guide piece U' and it is 15 adapted to rest between a pair of driven rollers V, the rotation of the driven rollers, however, being so timed as to avoid any appreciable stretching of the loosely felted 20 blanket or sheet delivered from the foraminous cylinder. By providing a pair of foraminous cylinders rotating in opposite directions with internal suction not only is the fiber felted more effectually, but each 25 surface only accumulates a portion of the fiber necessary for the full thickness of the blanket or sheet, and, consequently, but a small area of the surface of the cylinders is necessarily exposed for the accumulation of 30 fiber. The result of this is that a uniform product is secured and there is little or no tendency of the fiber to bank up or accumulate at the entrant angle between the cylinders.

Obviously, the rollers, cylinders, brush, etc., may be made of any desired length, and this is especially important, inasmuch as 35 material of the character herein contemplated must, for some uses, be made very wide. The large number of toothed rollers acting successively on the fiber in conjunction with the toothed cylinders not only reduces the fiber to a uniform flocculent condition, but distributes it uniformly and insures a felt of uniform thickness and insulating qualities.

It will be noted that the fiber is not separated into grades, but all portions are acted 45 upon uniformly with a view to preserving the body and substance of the flax plant in such manner that the whole may be combined in a sheet or blanket for insulating 50 purposes.

In Fig. 1 of the accompanying drawings, the direction in which the several cylinders and rolls rotate is indicated by appropriate curved arrows and the diameter and speed 55 of rotation per minute is indicated in order that the relative movement of the parts may be more readily understood without the necessity of reading the specification.

Having thus described my invention, what 60 I claim as new, and desire to secure by Letters Patent of the United States, is—

1. An apparatus for making insulating coverings which embodies means for disintegrating degummed and dried flax straw and forming the same into a flocculent mate-

rial, means for projecting said material into the air, a pair of foraminous rotary drums against which the material is projected and between which it is discharged, air suction apparatus in communication with the interior 70 of the drums whereby the material is held thereon in loose sheets which are fed toward each other and united by the rotation of the drums, segmental guards within the drums for relieving suction on the combined sheets 75 at the point of discharge from the drums, and means for pressing the combined sheets to form a covering.

2. In apparatus for the manufacture of insulating covering, the combination with a 80 preliminary cylinder having forwardly projecting teeth, feeding-in rolls for delivering straw to said cylinder, disintegrating rolls coöperating with said cylinder and having a surface movement reverse to that of the cylinder, a main cylinder having forwardly projecting teeth, a transfer roll for transferring the partially disintegrating fiber from the preliminary to the main cylinder, 85 a plurality of rolls coöperating with the 90 main cylinder and having forwardly projecting teeth, a brush for removing the fiber from the main cylinder, a casing surrounding said brush, a discharge duct with which the casing communicates, a pair of foraminous cylinders through which the air from 95 said duct is discharged and on which the fiber is arrested, means whereby air suction through the cylinders may be maintained, and guide rolls through which the deposited 100 fiber is conducted from the foraminous cylinders.

3. In an apparatus for forming insulating coverings from flax straw, the combination with means for disintegrating and making the straw into flocculent material embodying the fiber and woody portions, said means embodying a cylinder having forwardly projecting teeth, of a rotary brush having wiping arms moving in a path in proximity to the cylinder, diaphragms bridging the spaces between said arms, a casing in which the brush is mounted having a grated air entrance opening at the bottom, a discharge duct communicating with said casing and a pair of foraminous cylinders interposed in and bridging the discharge openings of said duct, with means whereby fiber deposited on said cylinders may be conducted away from the same in the form of a continuous sheet.

4. In apparatus for forming insulating coverings of fibrous material, the combination with the preliminary and main cylinders having forwardly projecting teeth, rolls coöperating with said cylinders and having forwardly projecting teeth but rotating in a direction whereby the proximate surfaces of the cylinders and rolls move in opposite directions, a transfer roll for transferring the 130

- material from one cylinder to the other and intermediate rolls for clearing the first mentioned rolls, of a rotary brush having wiping arms coöperating with the main cylinder to remove the fiber therefrom, a casing in which said brush is mounted having an air inlet opening at the bottom, a duct through which the fiber is discharged from said casing, a foraminous cylinder bridging the outlet of said duct, a suction box communicating with the foraminous cylinder and an internal guard lying in proximity to the periphery of said cylinder for relieving the air pressure at the point where the fiber is discharged from the cylinder.
5. In a machine for forming insulating coverings of fibrous material, the combination with the preliminary and main toothed cylinders, rolls coöperating with said cylinders for reducing the fiber to a flocculent
- 10
- 15
- 20

condition, a rotary brush for discharging the fiber from the main cylinder, a casing in which said brush is mounted having a grated air inlet opening at the bottom, and a flaring discharge duct with which said opening 25 communicates, of casings forming continuations of the walls of said duct, foraminous cylinders mounted in said casings and adapted to rotate in opposite directions toward each other, a suction chamber communicating with said foraminous cylinders and segmental guards located within the cylinders and extending forwardly from the point where their peripheries are in proximity, whereby the entrance of air on the discharge 30 side of the cylinders is prevented.
